DESIGN FOR A SWIM SUIT OR SIMILAR ARTICLE

Margit Fellegi Laszlo, Los Angeles, Calif., assignor to Cole of California Inc., Los Angeles, Calif.

Application December 4, 1944, Serial No. 116,686

Term of patent 7 years

(Cl. D3—17)

To all whom it may concern:

Be it known that I, Margit Fellegi Laszlo, a citizen of the United States of America, residing at Los Angeles, in the county of Los Angeles and State of California, have invented a new, original, and ornamental Design for a Swim Suit or Similar Article, of which the following is a specification, reference being had to the accompanying drawing, forming a part thereof.

The figures in the drawing are,

Figure 3 is a front perspective view on a reduced scale, of the trunk portion of the swim suit or similar article, showing the skirt portion open and the lacing on the side which is repeated on the other side; and

Figure 4 is a front perspective view of the trunk portion of the swim suit or similar article shown in Figure 1 with the sash unfastened and extended.

I claim:

The ornamental design for a swim suit or similar article, as shown and described.

MARGIT FELLEGI LASZLO.
